(57) **CLAIM**

The ornamental design for an infant water ski, as shown and described.

DESCRIPTION

FIG. 1 is a perspective view of the infant water ski of the invention, the broken lines in the drawing are for illustrative purposes only and form no part of the claimed design;

FIG. 2 is a front view of the infant water ski of FIG. 1;

FIG. 3 is a left side view of the water ski of FIG. 1, the right side being a mirror image thereof;

FIG. 4 is a rear view of the water ski of the invention;

FIG. 5 is a top view of the infant water ski of the invention; and,

FIG. 6 is a bottom view of the water ski of the invention.

1 Claim, 4 Drawing Sheets

FIG. 2

FIG. 3
